UNITED STATES PATENT OFFICE

2,302,627

TYPEWRITING MACHINE

Henry J. Hart, West Hartford, Conn., assignor to
 Royal Typewriter Company, Inc., New York,
 N. Y., a corporation of New York

Application April 9, 1941, Serial No. 387,745

22 Claims. (Cl. 197—63)

This invention relates to typewriting machines and more particularly to mechanism for adjustably positioning or setting stops for arresting or limiting movement of typewriter carriages in letter spacing or return directions. Mechanism embodying the invention is especially suited for adjustably positioning or setting margin stops.

United States Patent to Henry Joseph Hart Number 2,208,367, granted July 16, 1940, discloses margin stop setting mechanism including a resilient spring band which normally urges two carriage-mounted margin stops towards each other and towards a frame mounted center stop. Latches on the margin stops normally hold the stops in adjusted position and are adapted to be released respectively by bails mounted to rock on the carriage, there being two such bails, one associated with each margin stop latch. In accordance with the present invention a single latch releasing member or bail may be provided for selectively releasing the two stop latches.

An object of the invention is to provide a typewriter stop setting mechanism of the kind referred to in which the bail or other latch operating member is so positioned as to release the latch or latches with a minimum of binding or cramping of the stop on its supporting rod.

Another object is to provide stop setting mechanism of the kind referred to in which separate manually operable members are provided for moving the bail or other latch operating means to release either latch selectively and to insure against accidental releasing of both stop latches when it is desired to release only one of them.

A further object is to provide stop setting mechanism of the character referred to which is of simple, light and sturdy construction.

A further object is to provide stop setting mechanism of the character referred to and which includes manually operable means mounted on the typewriter main frame for controlling the adjustment of a stop or stops mounted on the carriage. Other objects will become apparent from a reading of the following detailed description, the appended claims, and the accompanying drawings, in which:

Figure 1 is a fragmentary front elevational view of a typewriter carriage showing parts of mechanism embodying the invention;

Figure 2 is a top plan view of an assembly of 50 some of the parts shown in Figure 1;

Figure 3 is a distorted diagrammatic plan view of a resilient stop-urging band and its mounting means;

Figure 4 is a rear perspective view of parts of a 55

typewriter carriage and mechanism embodying the invention applied thereto and drawn on an enlarged scale;

Figure 5 is a vertical section on the line 5—5 of Figure 1 and drawn on an enlarged scale;

Figure 6 is a fragmentary horizontal section on the line 6—6 of Figure 1 drawn on an enlarged scale and with some parts shown in elevation;

Figure 7 is a fragmentary vertical sectional view on the line 7—7 of Figure 6;

Figure 8 is a fragmentary transverse vertical section, partly in elevation, showing parts of the right hand margin stop control means in their 15 normal positions;

Figure 9 is an end elevation of means for controlling a right hand margin stop with parts shown in their operative positions;

Figure 10 is an end elevation showing mechanism for controlling the left hand margin stop, the parts being shown in their normal positions;

Figure 11 is a view similar to Figure 10, but showing the parts in their operative positions;

Figure 12 is an end elevation showing mechanism for controlling the right hand margin stop and means for locking it against operation when the mechanism for controlling the left hand margin stop is in its operative condition;

Figure 13 is an end elevation showing mechanism for controlling the left hand margin stop and means for locking it against operation when the mechanism for controlling the right hand margin stop is in its operative condition;

Figure 14 is a phantom perspective view of a 35 modified embodiment of the invention showing parts of stop setting mechanism in full lines and indicating their positioning with respect to a typewriter frame indicated in dot-dash lines;

Figure 15 is a fragmentary detailed view showing 40 a stop latch operating bail and mechanism for raising the bail for setting the left hand margin stop;

Figure 16 is a view similar to Figure 15 but showing mechanism for lowering the bail for setting the right hand margin stop;

Figure 17 is a fragmentary transverse vertical 45 sectional view of a typewriting machine equipped with stop setting mechanism of the kind shown in Figure 14;

Figure 18 is a vertical sectional view taken on the line 18—18 of Figure 17 with some parts omitted and some parts shown in elevation; and

Figure 19 is a top plan view showing associated margin stops, margin stop rod, and center stop.

Mechanism constructed and arranged to operate in accordance with the invention may be embodied in typewriting or like machines of various kinds.

The drawings show only such of the usual parts of a typewriter as are necessary in order to make clear the manner of applying stops and stop-setting mechanisms embodying the invention to typewriters generally. The known or usual parts of the construction shown in Figures 1 to 13, inclusive, are of the form used in the Royal Standard typewriter and include a main-frame-mounted track A, a main frame rear wall part B, and a carriage element C having a track 1 supported for letter-spacing and return movements on the track A by ball bearings 2. A platen or cylinder 3 is mounted between end plates 4 and 5 forming part of the carriage element. A scale D is supported on the carriage as at 6—6 and is provided along its upper edge with a work sheet and typing aligning scale 7, and along its bottom edge with a carriage positioning scale 8. Central pointers 9 and 10 formed on a type bar guide E cooperate with the scale D for assisting the operator to position the carriage. The guide E may be movable vertically for case shifting, but is held against horizontal travel. A center stop 11 of known kind is pivotally mounted as at 12 on the frame element B, and a line lock lever 13 is pivotally mounted as at 14 on the center stop 11 in a known manner. A tabular stop mounting assembly F is supported on the carriage, being connected at its opposite ends to the end plates 4 and 5 as at 15 and 16 respectively.

Margin stops respectively designated G and G' are mounted on and for adjustment along a margin stop rod H having transverse teeth 17 spaced along its upper face and being supported on and between the carriage end plates 4 and 5.

The left hand margin stop G includes a tubular body 18 formed with a lateral extension 19 which receives an adjustable abutment screw 20 adapted to cooperate with the center stop 11 in a manner to be described, a set screw 21 serving to hold the abutment screw 20 in adjusted position. A latch generally designated 22 is pivotally mounted as at 23 on the body 18, and is provided with a nose 24 adapted to fit between adjacent teeth 17 on the margin stop rod H for releasably securing the stop G in adjusted position on the rod H. The latch is formed with a horizontal arm 25 extending toward the center of the carriage, and a spring 26 held in place by a stud 27 is interposed between the body 18 and the horizontal arm 25 for yieldably urging the latch nose 24 toward the teeth 17 of the rod H. A vertical arm 28 integral with the horizontal arm 25 between the pivot 23 and latch nose 24 is provided with a roller 29 which serves as an actuator for releasing the latch 22 when the roller 29 is pressed upwardly in a manner to be described later. The vertical arm 28 is formed with a finger piece 30 and a companion finger piece 31 extends upwardly from the body 18. When it is desired to release the latch 22 manually, the two finger pieces 30 and 31 may be grasped between the thumb and forefinger and a squeezing action exerted.

The construction of the right hand margin stop G' is similar to that of the left hand stop G just described, with the exceptions that it is reversed as to right and left hand and the vertical arm 28' of the stop G' is integral with the horizontal arm 25' at the end thereof remote from the nose 24' whereby the latch will be released

from the rod H when the roller 29' is pressed downwardly. The reversely similar parts of the two stops G and G' are designated by corresponding reference characters, the characters applied to the stop G' being primed.

Means are provided for constantly urging both stops G and G' inwardly toward the center of the carriage and towards each other. The stop urging means comprises an elongated coil power spring I one end of which is connected to an ear 32' on the body 18' of the stop G'. From the ear 32' the spring I extends to the left as at 33 (see Figure 3), and around a sheave or roller 34 anti-frictionally journaled on a bracket 35 secured to the end plate 4 by a screw 36. The spring then extends to the right as at 37 and around a sheave or roller 34' anti-frictionally journaled on a bracket 35' secured to the end plate 5 by a screw 36'. Thence the spring extends to the left as at 38, and is connected to an ear 32 on the body 18 of the stop G.

To provide free journaling of the rollers, they are mounted by anti-friction ball bearings, the bearings for the right hand roller 34' being shown at 39' in Figure 5. Similar ball bearings, not shown, are provided for freely mounting the left hand roller 34.

In order to prevent accidental fouling or entanglement of the spring I with adjacent parts, a housing 40 substantially enclosing the entire spring and mounted under the margin stop rod H is secured to the brackets 35 and 35' as at 41 and 41'. The construction described thus far is in general similar to construction disclosed and claimed in Patent 2,208,367, previously referred to.

In accordance with the invention a single operating member or device mounted on the carriage is arranged to be selectively operable for releasing either latch 22 or 22' to permit the spring band I to move the associated stop G or G' up against the center stop. In the embodiment disclosed in Figures 1 to 13, inclusive, the operating member comprises a bail J including a bail bar 42 extending longitudinally of and directly over the margin stop rod H. Bail arms 43 and 44 projecting rearwardly from the bar 42 are mounted pivotally on the carriage as at 45 and 46 so as to permit the bail to rock about an axis horizontally offset from and exterior of the bar 42. Mounting of the roller 29 of the latch 22 at a level above the roller 29' of the latch 22' permits the mounting of the bail bar 42 between the rollers 29 and 29' so that the rollers are engageable respectively with opposite faces of the bar. When the bail is swung upwardly from its normal or neutral position the roller 29 will be lifted to release the latch 22 and permit the band I to move the stop G toward the right, whereas when the bail is rocked downwardly the bar 42 will push down on the roller 29' to release the latch 22' and permit the spring band I to draw the stop G' to the left. The engagement of the rollers 29 and 29' with the bail bar 42 along a line substantially directly above the rod H eliminates the exertion of a turning or twisting force on the margin stops and thereby prevents binding or cramping of the stops on the rod H.

Means for lowering the bail to release the right hand margin stop G' includes a manually operable lever member 47 pivoted as at 48 on the end plate 5. The lever 47 is formed with a seat 49 which normally engages a pin 50 fixed to an extension 51 of the bail arm 44 so as to support the bail in its normal or neutral position in which

it has no operative engagement with the latch rollers 29 and 29'. The lever 47 is formed with a cam slot 52 the inclination of which is such that when the lever is rocked counterclockwise from the position shown in Figure 8 to the position shown in Figure 9 it will cam the pin 50 downwardly and rock the bail so as to press downwardly on the roller 29' of the latch 22' thereby releasing the margin stop G'. Preferably the groove 52 terminates in a seat 53 adapted to receive the pin 50 so as to retain the bail in its lowered position until the lever 47 is manually pushed back to its normal position shown in Figure 8. The lever is yieldably restrained from moving from its normal position by a spring 54 held on the carriage end plate 5 by screws 55 and 56, the upper end of the spring pressing against a flat surface 57 on the lever 47. The normal position of the lever 47 may be adjusted nicely by means of an eccentric cam 58 secured to the end plate 5 by a screw 59. As will be described later, control means mounted at the left hand end of the carriage are adapted to raise the bail J for releasing the latch 22 of the left hand margin stop. To permit the bail to be raised without interference by the lever 47, the upper part of the lever is cut back as at 60 so as to provide for free uninterrupted upward movement of the pin 50.

Figures 10, 11, and 13 show manually operable control means for raising the bail J to press upwardly on the roller 29 and release the latch 22. A manually operable lever member 61, pivoted as at 62 to the carriage end plate 4, is provided with a finger 63 the end of which normally overlies a pin 64 on an extension 65 of the arm 43, thereby normally preventing upward movement of the bail. The finger 63, which normally prevents upward movement of the bail, cooperates with the seat 49 on the manually operable lever 47 which normally prevents downward movement of the bail to hold the bail normally in a neutral position in which it has no operative engagement with the latch actuator rollers 29 and 29'. The manually operable lever 61 is formed with a cam slot 66 the inclination of which is such as to push upwardly on the pin 64 and rock the bail upwardly when the lever 61 is rocked from its normal position, shown in Figure 10, to its operative position, shown in Figure 11. Preferably, the groove 66 terminates in a seat 67 adapted to receive the pin 64 for maintaining the bail raised until the lever 61 is manually pushed back to its normal position. The lever is held against accidental displacement from its normal position by a spring 68 held on the carriage end plate 4 by screws 69 and 70, the spring bearing against a flat surface 71 on the bottom of the lever 61. The normal position of the lever 61 may be adjusted nicely by means of an eccentric stop 72 secured to the end plate 4 by a screw 73. In order to enable the bail J to be moved downwardly by operation of the lever 47 in the manner previously described the lever 61 is cut away as at 74 to provide clearance for uninterrupted downward movement of the pin 64.

In operation, assuming that it is desired to set the margin stop G so as to fix the left hand margin at twenty letter spaces and to set the stop G' so as to fix the right hand margin at seventy letter spaces, the cam lever 61 is swung forwardly so as to raise the pin 64 and rock the bail J upwardly. This will move the roller 29 upwardly and lift the latch nose 24 out of engagement with the toothed rod H, permitting the 75

spring band I to pull the stop G toward the right to abut against a buffer 75 pivoted as at 14 on the center stop and provided with a cushioning spring 76. The carriage may then be moved until the pointer 9 or the pointer 10 registers with the marking "20" on the scale D. The lever 61 will then be swung rearwardly to the position shown in Figure 10 thereby lowering the bail to its neutral position and permitting the spring 26 to return the latch 22 to its holding position, whereupon the stop G will be locked in adjusted position on the rod H.

In order to set the right hand stop G' the cam lever 47 is swung forwardly from the position shown in Figure 8 to the position shown in Figure 9, thereby lowering the bail J and pushing downwardly on the roller 29' of the latch 22' which is thus disengaged from the rod H, permitting the band I to pull the stop G' up against the line lock lever 13 on the margin stop 11. The carriage is then moved until the pointer 9 or the pointer 10 registers with the marking "70" on the scale D and the lever 47 is then pushed rearwardly to the position shown in Figure 8, thereby raising the bail to its neutral position and permitting the latch 22' to reengage the rod H and lock the stop G' in adjusted position on the rod.

It will be observed that after setting of the left hand margin stop G by operation of the lever 61 and upon return of the lever 61 to its normal position, the seat 49 on the lever 47 will retain the pin 50 and consequently the bail J against accidental downward movement so that it is not possible for the bail to overthrow downwardly. Therefore the right hand stop G' will not be released from the rod H unless the lever 47 is moved. Similarly, during operation of the lever 47 after setting the right hand margin stop G', the finger 63 on the lever 61 will prevent upward overthrow of the bail upon return of the lever 47 to its Figure 8 position and consequently will prevent unintentional release of the latch 22' of the stop G'.

It is desirable to prevent swinging of both operating members 47 and 61 to their operative positions at the same time because, if such simultaneous movement were permitted or if movement of one of these members were permitted after the other member already had been moved to operative position, the bail would be strained by being moved downwardly at its right hand end and upwardly at its left hand end. Accordingly, means are provided for locking either of the manually operable levers 47 and 61 against operation when the other of the levers has been moved to its operative position. In the embodiment shown an ear 77 on the lever 47 is positioned so as normally to pass over an ear 78 on the bail J when the bail is in its normal position and the lever 47 is rocked to its operative position. If, however, the bail has been raised to the position shown in Figures 11 and 12 by operation of the lever 61, the bail carried ear 78 will be disposed in the path of the ear 77 on the lever 47 so as to prevent swinging of the lever 47 to its operative position. Similarly, the operating lever 61 is provided with an ear 79 which is so positioned as to pass under an ear 80 on the bail J when the bail is in its normal position and the lever 61 is rocked to its operative position. If, however, the bail is in its lowered position, as shown in Figures 9 and 13, the ear 80 on the bail will be disposed in the path of the ear 79 on the lever 61 so as to prevent swinging of the lever 61 to its operative position. Figures 14 to 19, inclusive, show a modifica-

tion in which the manually operable means for releasing the margin stop latches includes finger keys mounted on the main frame and constrained against movement in the direction of carriage travel.

The typewriter shown includes a main frame A', carriage B', platen C', combined platen and carriage locating scale D' supported on the carriage, and type bar guide E'. The main frame includes a rear wall 101, end walls 102 and 103, and a front wall or cover 104. Mounted on the main frame is an escapement frame 105 supported on a fixed track 106, which, through ball bearings 107, mounts a carriage bearing rail 108 extending between and connecting carriage end plates 109 and 110.

The carriage B' is urged to the left in letter space direction by a spring motor (not shown) of a known kind, and is controlled by escapement mechanism supported on the frame 105. The escapement mechanism also may be of a known kind, and only so much of it is shown in the drawings as may be of assistance in understanding the present invention. It includes an escapement wheel 111 and an escapement pinion 112 journaled on the frame 105, the pinion 112 being arranged to mesh with a toothed escapement rack 113 carried by a bar 114 mounted on the carriage by means (not shown) permitting the bar and rack 113 to be raised out of engagement with the pinion for rendering the escapement mechanism ineffective.

Central pointers 115 and 116 formed on the type bar guide E' cooperate with the scale D' for assisting the operator to position the carriage. A center stop 117 is pivotally mounted as at 118 on a bracket 119 on the frame wall 101. A tabular stop mounting assembly F' is supported on the carriage, being connected at its opposite ends to the end plates 109 and 110 by studs 120 and 121 respectively.

Stop setting mechanism embodying the invention is adapted to be incorporated in typewriters equipped with tabulating mechanism without interference in the operation of the tabulating mechanism or the stop setting mechanism. Figure 17 shows a tabulating stop finger 122 pivoted as at 123 on the bracket 119. One end of an adjustable link 124 is pivotally connected as at 125 to the center stop 117, the other end of the link 124 being pivotally connected as at 126 to the tabulating finger 122. An extension 127 on the center stop is connected by a link 128 to the upper end of a rock arm 129 mounted on a shaft 130 carried by the frame A. A tabulator key lever 131 on the shaft 130 has an arm 132 provided with an ear 133 extending behind the rock arm 129. Normally the key lever 131 is held up against a stop 134 by a spring 135 anchored on a part 136 of the frame A. When the key lever 131 is depressed the arms 134 and 129 are rocked to pull the link 128 and rock the center stop and tabulating finger in a manner well known in the art. A lifting lever 137 pivoted at 138 on the escapement frame 105 has a downwardly extending arm 139 engageable by the center stop extension 127 to be rocked thereby so as to cause an arm 140 on the lifting lever to raise the rack 113 out of engagement with the escapement pinion 112.

Right and left hand margin stops, respectively designated K and K', are mounted on and for adjustment along a margin stop rod L having transverse teeth 141 spaced along its upper

face and being supported on and between the carriage end plates 109 and 110.

The right hand margin stop K includes a tubular body 142 formed with a lateral extension 143 which receives an adjustable abutment screw 144 adapted to cooperate with the center stop 117, a set screw 145 serving to hold the abutment screw 144 in adjusted position. A latch generally designated 146 is pivotally mounted as at 147 on the body 142, and is provided with a nose 148 adapted to fit between adjacent teeth 141 on the margin stop rod L for releasably locking or securing the stop K in adjusted position on the rod L. The latch is formed with a horizontal arm 149 extending toward the center of the carriage, and a spring 150 is interposed between the body 142 and the horizontal arm 149 for yieldably urging the latch nose 148 toward the teeth 141 of the rod L. A roller 151 is mounted on the arm 149 and cooperates with mechanism located on the main frame A to release the latch 146.

The construction of the left hand margin stop K' is similar to that of the right hand stop K with the exceptions that the two stops are reversed as to right and left hand, and the arm 149' on the latch 146' of the stop K' is provided with a vertical extension 149'' which mounts the roller 151' higher than the roller 151 of the stop K. Otherwise the reversely similar parts of the two stops are designated by corresponding reference characters, those applied to parts of the stop K' being primed.

Means provided for urging the stops towards each other and each toward the center stop may be the same as the stop urging means described in connection with Figures 1 to 13, inclusive. A spring band M has its ends connected to ears 152 and 152' on the stops K and K' respectively, and is trained around rollers 153 and 153' journaled at 154 and 154' on brackets 155 and 155' secured by screws 156 and 156' to the carriage end plates 110 and 109. A housing 157 substantially encloses the spring band. In operation the roller 151 on the latch 146 of the stop K is pressed downwardly to disengage the latch nose 158 from the margin stop rod L to permit the spring band M to move the margin stop K up against the center stop 117. Lifting of the roller 151' on the latch 146' will disengage the nose 148' from the rod L so as to permit the spring band M to move the stop K' up against the center stop 117.

For lowering and raising the rollers 151 and 151', respectively, a bail N including a bail bar 158 and arms 159 and 160 is pivotally mounted on the end plates 109 and 110 as at 161 and 162 so as to rock about an axis horizontally displaced from and to the rear of the rod L. The bar 158 extends between the rollers 151 and 151', the rollers and bar being disposed directly above the margin stop rod L. A front edge portion 163 of the bail bar projects in front of the margin stop rod L.

Means for operating the bail is mounted on the main frame and is adapted to cooperate with the bail irrespective of the position of the carriage on the frame. A shiftable link member 164 formed with a notch 165 which receives the front edge portion 163 of the bail is mounted for vertical movement on the frame by means of parallel carrying links 166 and 167 which are pivoted to the link 164 as at 168 and 169, respectively, and are pivoted as at 170 and 171 to brackets 172 and 173 supported on the rear wall 101 of the main frame. The intermediate portion of the

link 164 is formed with a rearwardly extending offset 164^a to enable the link to extend past and yet clear the conventional typewriter parts, such as the escapement frame 105.

The lower end of the link 164 is offset rearwardly as at 164^b and is provided with a pin 174 which extends to both sides of the link. On the right side of the link a shaft 175 is journaled in brackets 176 and 177 supported on the frame rear wall 101. A cam plate 178 secured to the shaft 175 is formed with a seat 179 which normally supports the pin 174 and with it the link 164 and the bail N in their neutral or normal positions wherein the bail has no operative engagement with either the roller 151 or the roller 151'. The cam plate 178 is formed with a cam groove 180 of such shape that when the plate 178 is rocked counter-clockwise, as viewed in Figure 16, the pin 174 and link 164 will be drawn downwardly and the bail N will be rocked downwardly so as to depress the roller 151 and release the latch 146 of the stop K, thus enabling the spring band M to pull the stop K toward the left and against the center stop 117. For operating the shaft 175 and cam plate 178 a rock arm 181 secured to the shaft 175 is pivoted as at 182 to the rear end of a pull link 183, the forward end of which is pivoted as at 184 to a lever 185 pivoted on a rod 186 carried on a part 136 of the main frame. An arm 187 of the lever 185 extends upwardly for connection to a restoring spring 188 anchored to a post 189 on the frame part 136. A stop lug 190 integral with the arm 187 abuts against the frame part 136 for limiting the restoring movement of the lever 185. A push key 191 extends through the front wall 104 of the machine frame and the frame part 136 and is engageable with an ear 192 on the arm 187 of the lever 185. Pushing of the key 191 inwardly rocks the lever 185 clockwise as viewed in Figure 17 to pull on the link 183 and rock the cam plate 178 counter-clockwise, thereby moving the pin 169 and the link 164 downwardly, rocking the bail N and releasing the latch on the stop K as previously described. It will be observed that when the cam plate 178 is in its normal position as shown in full lines in Figure 16, clearance is provided above the pin 174 for permitting the latter to be moved upwardly for setting of the left hand margin stop K' in a manner to be described. For providing this clearance the upper part of the lever 178 may be cut away as indicated at 193.

Similar but reversely operating mechanism provided for raising the link 164 and bail N to release the latch 146' and enable adjustable setting of the margin stop K' includes a shaft 194 carried by brackets 195 and 196 supported on the rear frame wall 101. A cam plate 197, fixed to the shaft 194, is provided with an upper finger portion 198 which normally overlies the pin 174 for normally preventing upward movement of the pin and the link 164. The cam plate 197 is formed with a groove 199 of such configuration that rocking of the cam plate counter-clockwise from the position shown in full lines to the position shown in dotted lines in Figure 15 will raise the pin 174 and the link 164 so as to lift the bail N and roller 151' and thus release the latch 146' and enable the spring band M to draw the stop K' up against the center stop. For rocking the shaft 194 and cam plate 197, a rock arm 200 fixed to the shaft 194 is pivoted as at 201 to the rear end of a link 202, the forward end of which is pivoted as at 203 to a lever 204 pivoted as at 205 on the rod 186. An arm 206 of the lever 204 has

5 connected to it a restoring spring 207 which is anchored similarly to the anchoring of the restoring spring 188. A push key 208 extending through the frame front wall 104 is engageable with an ear 209 on the arm 206 of the lever 204 for rocking the lever when the key 208 is pressed. Such rocking of the lever pulls forwardly on the link 202 and rocks the shaft 194 and cam plate 197 counter-clockwise as viewed in Figure 15 so as to release the latch 146' in the manner already described. It will be observed that the shape of the cam plate 197 is such as to provide clearance to permit downward movement of the pin 174 when the cam plate is in its normal position and the other cam plate 178 is operated to release the latch 146 of the stop K.

20 The procedure followed in setting or adjusting the positions of the margin stops K and K' is similar to that described above in connection with the setting of the margin stops G and G' of the embodiment disclosed in Figures 1 to 13, inclusive. When the cam plate 197 is returned to its normal position after setting the left hand stop K', downward overthrow of the link 164 and bail N will be prevented by engagement of the pin 174 with the seat 179 on the cam plate 178. When the cam plate 178 is returned to its normal position, after setting the right hand stop K, upward overthrow of the link 164 and bail N will be prevented by engagement of the pin 174 with the finger 198 on the cam plate 197.

25 The mechanisms disclosed herein embody the invention in the now preferred forms, but it will be understood that changes may be made without departing from the invention as defined in the claims.

I claim:

1. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; an actuator movable in one direction for releasing the securing means associated with one of said margin stops; an actuator movable in the opposite direction for releasing the securing means associated with the other of said margin stops; an operating member movably mounted on said other element and extending longitudinally of the direction of adjustment of said margin stops and between said actuators; and means for moving said operating member in opposite directions for selectively moving said actuators in their respectively releasing directions.

2. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; an actuator movable in one direction for releasing the securing means associated with one of said margin stops; an actuator movable

in the opposite direction for releasing the securing means associated with the other of said margin stops; an operating bar movably mounted on said other element and extending longitudinally of the direction of margin stop adjustment and between said actuators; and means for moving said bar bodily in opposite directions for selectively moving said actuators in their respectively releasing directions.

3. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; an actuator movable in one direction for releasing the securing means associated with one of said margin stops; an actuator movable in the opposite direction for releasing the securing means associated with the other of said margin stops; an operating bar extending longitudinally of the direction of margin stop adjustment and between said actuators; means pivoting said bar on said other element to swing bodily about an axis offset from and exterior of the bar; and means for rocking said bar bodily in opposite directions about said offset axis for selectively moving said actuators in their respectively releasing directions.

4. In a typewriter or like machine; a frame element; a carriage element mounted thereon for letter-spacing and return movements; a center stop mounted on one of said elements; a toothed rod mounted on the other of said elements and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; actuators connected respectively to said latches and being movable in opposite directions for disengaging the respectively connected latches from said rod; a bail pivoted to swing on said other element about an axis horizontally offset from said rod and having a bail bar extending along and adjacent said rod and between said actuators; and means for rocking said bail in opposite directions for selectively moving said actuators in their latch-disengaging directions.

5. In a typewriter or like machine; a frame element; a carriage element mounted thereon for letter-spacing and return movements; a center stop mounted on one of said elements; a toothed rod mounted on the other of said elements and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; a bail pivoted to swing on said other element about an axis horizontally offset from said rod and having a bail bar extending along and directly over said rod; actuators connected respectively to said latches and being disposed respectively above and below said bar and being movable upwardly and downwardly respectively

for disengaging the respectively associated latches from said rod; and means for swinging said bail to move said bar selectively upwardly and downwardly.

5. In a typewriter or like machine; a frame element; a carriage element mounted thereon for letter-spacing and return movements; a center stop mounted on one of said elements; a toothed rod mounted on the other of said elements and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; a bar movably mounted on said other element and extending along and directly over said rod; actuators connected respectively to said latches and being disposed respectively above and below said bar and being movable by said bar upwardly and downwardly respectively for disengaging the respectively associated latches from said rod; and means for moving said bar selectively upwardly and downwardly.

7. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; releasing means for releasing respectively the securing means associated with said margin stops including a manually operable member operation of which effects releasing of the securing means associated with one of said margin stops, and another manually operable member operation of which effects releasing of the securing means associated with the other of said margin stops; and means for locking one of said manually operable members against operation when the other of said manually operable members is operative.

8. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; releasing means for releasing respectively the securing means associated with said margin stops including a manually operable member operation of which effects releasing of the securing means associated with one of said margin stops, and another manually operable member operation of which effects releasing of the securing means associated with the other of said margin stops; and means for locking either of said manually operable members against operation when the other of said manually operable members is operative.

9. In a typewriter or like machine; a frame element; a carriage element mounted thereon for letter-spacing and return movements; a center stop mounted on one of said elements; a pair of

margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; a device for selectively releasing the securing means associated with said margin stops; a first manually operable member for moving said device to release the securing means associated with one of said margin stops; a second manually operable member for moving said device to release the securing means associated with the other of said margin stops; and means responsive to operating movement of either one of said manually operable members to releasing position for preventing operation of the other manually operable member until said one manually operable member has been returned to non-releasing position.

10. In a typewriter or like machine; a frame element; a carriage element mounted thereon for letter-spacing and return movements; a center stop mounted on one of said elements; a pair of margin stops cooperable with said center stop; means mounting said margin stops on the other of said elements for adjustment towards and from each other in the direction of carriage travel; means urging said margin stops towards each other; releasable means respectively securing said margin stops in adjusted positions on said mounting means; a device mounted on said other element for movement from a normal ineffective position in opposite directions respectively for selectively releasing said securing means; a manually operable member for moving said device in one direction only from said normal position; and another manually operable member for moving said device in the opposite direction only from said normal position.

11. In a typewriter or like machine; a frame element; a carriage element mounted thereon for letter-spacing and return movements; a center stop mounted on one of said elements; a toothed rod mounted on the other of said elements and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; actuators connected respectively to said latches and being movable in opposite directions for disengaging the respectively connected latches from said rod; a bail pivoted to swing on said other element about an axis horizontally offset from said rod and having a bail bar extending along and adjacent said rod and between said actuators, said bail bar being adapted to normally occupy a neutral position in which it has no effective engagement with said actuators; a manually operable member for rocking said bail in one direction only from said neutral position for moving one of said actuators in its latch-disengaging direction; and another manually operable member for rocking said bail in the other direction only from said neutral position for moving the other of said actuators in its latch-disengaging direction.

12. In a typewriter or like machine; a frame element; a carriage element mounted thereon for letter-spacing and return movements; a center stop mounted on one of said elements; a

toothed rod mounted on the other of said elements and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; actuators connected respectively to said latches and being movable in opposite directions for disengaging the respectively connected latches from said rod; a bail pivoted to swing on said other element about an axis horizontally offset from said rod and having a bail bar extending along and adjacent said rod and between said actuators, said bail bar being adapted to normally occupy a neutral position in which it has no effective engagement with said actuators; a pin on one end of said bail; a manually operable member pivoted on said toothed rod mounting element and having a seat cooperable with said pin for normally maintaining said bail bar in said neutral position and having a cam groove cooperable with said pin, said manually operable member being adapted upon being moved about its pivot, and through the cooperation of said cam groove with said pin, to move the pin and bail bar in one direction from said neutral position for moving one of said actuators in its latch-disengaging direction; a second pin on the other end of said bail; and a second manually operable member pivoted on said toothed rod mounting element and having a cam groove cooperable with said second pin for moving the bail bar in the opposite direction from said neutral position for moving the other of said actuators in its latch-disengaging direction, each manually operable member being formed to provide clearance for movement of the associated pin when that member is in its normal or inactive position and the other manually operable member is actuated to move said bail.

13. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; an actuator movable in one direction for releasing the securing means associated with one of said margin stops; an actuator movable in the opposite direction for releasing the securing means associated with the other of said margin stops; an operating member extending longitudinally of the direction of adjustment of said margin stops and between said actuators; means mounting said operating member movably on said carriage; and means for moving said operating member in opposite directions for selectively moving said actuators in their respectively releasing directions.

14. In a typewriter or like machine; a main frame; a carriage mounted thereon for letter-spacing and return movements; a center stop on said frame; a toothed rod mounted on said carriage and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted

positions; actuators connected respectively to said latches and being movable in opposite directions for disengaging the respectively connected latches from said rod; a bail pivoted on said carriage to swing about an axis horizontally offset from said rod and having a bail bar extending along and adjacent said rod and between said actuators; and means for rocking said bail in opposite directions for selectively moving said actuators in their latch-disengaging directions.

15. In a typewriter or like machine; a main frame; a carriage mounted thereon for letter-spacing and return movements; a center stop on said frame; a toothed rod mounted on said carriage and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; actuators connected respectively to said latches and being movable in opposite directions for disengaging the respectively connected latches from said rod; a bail pivoted on said carriage to swing about an axis horizontally offset from said rod and having a bail bar extending along and adjacent said rod and between said actuators; a manually operable member for rocking said bail in one direction for moving one of said actuators in its latch-disengaging direction and for locking said bail in the position to which it has thus been rocked; and another manually operable member for rocking said bail in the opposite direction for moving the other of said actuators in its latch-disengaging direction and for locking said bail in the position to which it has thus been rocked.

16. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; releasing means for releasing respectively the securing means associated with said margin stops including a manually operable member operation of which effects releasing of the securing means associated with one of said margin stops, and another manually operable member operation of which effects releasing of the securing means associated with the other of said margin stops; and means for locking either of said manually operable members against operation when the other of said manually operable members is operative.

17. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; means for selectively releasing the securing means including a bar extending longitudinally of the line of adjustment of said margin stops on said carriage; means mounting said bar on said carriage to move in one direction for releasing one of said

securing means and in the opposite direction for releasing the other of said securing means; and means for moving said bar selectively in said directions including a shifting member having portions engageable with opposite faces of said bar, means mounting said member shiftably on said main frame, and manually operable means on said main frame for shifting said member.

18. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; means for selectively releasing the securing means including a bar extending longitudinally of the line of adjustment of said margin stops on said carriage; means mounting said bar on said carriage to move in one direction for releasing one of said securing means and in the opposite direction for releasing the other of said securing means; and means for moving said bar selectively in said directions including a shift link extending transversely to said bar and having a notch which receives an edge portion of the bar for relative sliding movement, means mounting said shift link on said frame for shifting movement transversely of said bar, and manually operable means on said frame for shifting said shift link.

19. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; means for selectively releasing the securing means including a bar extending longitudinally of the line of adjustment of said margin stops on said carriage; means mounting said bar on said carriage to move in one direction for releasing one of said securing means and in the opposite direction for releasing the other of said securing means; and means for moving said bar selectively in said directions including a shift link extending transversely to said bar and having a notch which receives an edge portion of the bar for relative sliding movement, a pair of spaced carrying links each pivoted to said frame and to said shift link to thereby mount said shift link on said frame for shifting movement transversely of said bar, and manually operable means on said frame for shifting said shift link.

20. In a typewriter or like machine; a main frame; a carriage mounted thereon for letter-spacing and return movements; a center stop on said frame; a toothed rod mounted on said carriage and extending in the direction of carriage travel; a pair of margin stops mounted for adjustment on said rod and being cooperable with said center stop; means urging said margin stops towards each other; latches on said margin stops respectively engageable with said toothed rod for releasably securing said margin stops in adjusted positions; actuators connected respectively to said latches and being movable in opposite directions for disengaging the respectively connected latches from said rod; a bail pivoted on said car-

riage to swing about an axis horizontally offset from said rod and having a bail bar extending along and adjacent said rod and between said actuators; and means for rocking said bail in opposite directions for selectively moving said actuators in their latch-disengaging directions including a shift link extending transversely to said bail bar and having a notch which receives an edge portion of the bail bar for relative sliding movement, means mounting said shift link on said frame to shift transversely of said bail bar, and manually operable means on said frame for shifting said shift link.

21. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; means for selectively releasing the securing means including a bar extending longitudinally of the line of adjustment of said margin stops on said carriage; means mounting said bar on said carriage to move in one direction for releasing one of said securing means and in the opposite direction for releasing the other of said securing means; and means for moving said bar selectively in said directions including a shift link extending transversely to said bar and having a notch which receives an edge portion of the bar for relative sliding movement, means mounting said shift link on said frame for shifting movement transversely of said bar, a pin on said shift link extending transversely to the direction of shifting thereof, and manually operable means including a cam

5 member pivoted on said frame and having a cam surface cooperable with said pin for shifting said link.

22. In a typewriter or like machine; a main frame; a carriage mounted thereon for letter-spacing and return movements; a center stop on said frame; a pair of margin stops cooperable with said center stop; means mounting said margin stops on said carriage for adjustment in the direction of carriage travel; means for urging said margin stops towards each other; releasable means respectively securing said margin stops in adjusted positions on said carriage; means for selectively releasing the securing means including a bar extending longitudinally of the line of adjustment of said margin stops on said carriage; means mounting said bar on said carriage to move in one direction for releasing one of said securing means and in the opposite direction for releasing the other of said securing means; and means for 15 moving said bar selectively in said directions including a shift link extending transversely to said bar and having a notch which receives an edge portion of the bar for relative sliding movement, means mounting said shift link on said frame for shifting movement transversely of said bar, a pin carried by said shift link and extending transversely to the direction of shifting thereof, a first cam member movably mounted on said frame and being cooperable with said pin for shifting said link in one direction from a neutral position and back to said neutral position, a second cam member movably mounted on said frame and being cooperable with said pin for shifting said link in the opposite direction from said neutral position and back to said neutral position, and 20 manually operable means mounted on said frame for selectively operating said two cam members.

HENRY J. HART.
